HEAD MOTION FOR LOOMS

William M. Wattie, Worcester, Mass., assignor to
Crompton & Knowles Loom Works, Worcester,
Mass., a corporation of Massachusetts

Application July 19, 1934, Serial No. 736,065

4 Claims. (Cl. 139—77)

This invention relates to improvements in head motions for looms, more particularly the so-called Knowles head, and it is the general object of the invention to provide improved means for 5 withstanding the horizontal strains of the vibrator levers in a head of large capacity.

The Knowles head operates with two oppositely rotating mutilated driving cylinder gears between which move a set of vibrator gears pivoted to 10 vibrator levers and positioned by pattern mechanism to have driving relation with one or the other of the cylinders. The vibrator gears are attached to connectors which in turn rock levers connected to the harnesses or boxes. The vibrator 15 gears are driven by a force derived from the cylinders, but they are held in place to receive this force by the vibrator levers which must be held against longitudinal or horizontal motion toward and from the gears to correctly position the 20 vibrator gears.

The outer end of each vibrator lever is provided with an open slot bearing which fits over a stationary heel pin. In order to hold the bearing in proper vertical position with respect to the heel pin a so-called shell or cap is used. An early 25 form of cap is shown in patent to Knowles No. 134,992, the cap in that instance having contact with a large part of the rounded outer end of the vibrator lever. At a later time the contact between the shell and lever was reduced as shown 30 in McGuiness Patent No. 865,264 where a rib on the under side of the shell contacts with a surface on the end of the vibrator lever concentric with the heel pin axis. The patent to Unwin 1,739,189 35 shows the form of heel pin used in recent years in which the vibrator lever itself is provided with a small boss having a surface ground concentric with the heel pin axis and engaging the under side of the shell.

40 So far as I am aware the only connection between the shell and the heel pin which would operate to restrain motion of the vibrator levers are the structures shown in the aforesaid patents, that is, a part of the lever itself is confined between the shell and pin to resist vertical motion. The strains in the vibrator levers incident to lifting the harnesses or shuttle boxes, however, are all in a horizontal direction and previous constructions have been such as to require the heel 45 pin to withstand all of these strains. It is an important object of my present invention to provide means for coupling the shell to the pin in such a way that the horizontal strains imposed upon the pin can be shared with the shell and the combined resistance of the shell and pin can be used 50

5 to prevent deflection of the latter. This connection may take the form of a block fitting snugly around the heel pin and having surfaces to fit closely the inner surface of the shell.

As heretofore constructed the shell has been 5 made of cast iron molded to a parti-cylindrical form. It is a further object of my present invention to make the heel shell of angle iron or steel and dispose the shell so that one of the webs of the angle will resist bending or flexing in a 10 horizontal plane.

With these and other objects in view which will appear as the description proceeds, my invention resides in the combination and arrangement of parts hereinafter described and set forth in the 15 claims.

In the accompanying drawing, wherein a convenient embodiment of my invention is set forth,

Fig. 1 is a top plan view of a Knowles head 20 having my invention applied thereto,

Fig. 2 is a vertical section on line 2—2 of Fig. 1,
Fig. 3 is an enlarged vertical section on line 3—3, Fig. 1, with the heel pin removed,

Fig. 4 is a diagrammatic view showing the 25 Knowles head with harness connections and indicating how my present invention will resist bending of the heel pin, and

Fig. 5 is a detail end elevation of the heel shell, 30 in the direction of arrow 5, Fig. 1.

Referring to Fig. 4, I have designated the 35 Knowles head generally at K and have shown diagrammatically a jack harness lever 10 pivoted at 11 and having attachment with a flexible connector 12 trained around appropriate sheaves to move a harness frame 13. The latter has a 35 thread eye 14 through which one of the warp threads W of the loom passes. The reed 15 beats up the filling to make cloth C which passes over the breast beam 16, and the warp is guided over the whip roll 17. It is to be understood that the 40 operation of the loom requires that the warp threads be separated as shown in Fig. 4, some of them being in the top shed following along line a, while others are in the lower shed following along line b. I have shown but one vibrator 45 lever and harness connection in the diagrammatic view, and the parts are in such position as to move the warps to the top shed along line a.

As shown more particularly in Figs. 1 and 2 the loom arch 20 supports a pair of side plates 21 and 50 22 which support top and bottom shafts 23 on which are mounted the mutilated top and bottom cylinders 24 and 25, respectively. A pattern cylinder 26 is also journaled in the head frame and serves to feed the pattern chain P, indicated in 55

Fig. 4, which determines the sequence in which the harnesses and boxes move.

A set of vibrator levers 30 are provided, each lever having an inner end 31 guided by a comb 32 and arranged to cooperate with a knife 33 which periodically locks the vibrator lever against improper vertical motion. The outer end of each vibrator lever is provided with a downwardly facing open bearing 35 the top of which is semi-cylindrical to fit over a fixed heel pin 36. The latter extends between the frames 21 and 22 and may be held in place by screws 37. A guide comb 38 fastened to the head frame positions the outer ends of the vibrator levers.

15 Each vibrator lever has rotatably mounted thereon a vibrator gear 40 which has two sets of teeth separated by blank spaces, and each gear is pivotally attached to a connector 41 which has driving relation with the harness jack 10. An 20 arcuate slot 42 in the gear receives a stop stud 43 carried by the lever 30.

By means of the parts shown in Figs. 1 and 2 the connector 41 can be moved to the right from the position shown in Fig. 2, or if in the right 25 hand position can be moved to the left either to depress or raise the harness frame 17. The mutilated gears turn continuously and are operationally related to the vibrator gears turning the latter in one or the other direction in well-known 30 manner.

An inspection of Figs. 2 and 4 will show that when the pivotal connection 45 between the vibrator gear and connector 41 is in the left hand 35 position, as shown in Fig. 2, the warp will lie along the upwardly inclined line *a* and will exert a downward strain on the jack pin, the effect of which is to tend to move the vibrator lever horizontally to the right as viewed in Fig. 1. When the vibrator gear shown in Fig. 2 starts to 40 turn in a right hand direction the connector 41 will move to the right and the warp threads will descend and when they are in a substantially straight line between the whip roll and the breast beam they will exert little or no horizontal strain 45 on the vibrator lever.

As the vibrator gear continues to rotate, however, the connector is moved farther to the right and the warp controlled by the harness 13 is inclined downwardly along the line *b*. The warp 50 resists this motion and exerts a pull in the lower part of the connection 12 which is transmitted through the jack lever 10, tending to move the vibrator lever to the left as viewed in Fig. 2. It will be seen therefore that each vibrator lever is 55 acted upon by forces tending to move it horizontally both to the right and left. Since the heel pin fits closely into the open ends of the vibrator levers it has transmitted thereto the horizontal strains of the vibrator levers.

60 If the pattern is such that half of the warp threads are always in the top shed and the other half in the bottom shed, and the warp is evenly distributed so far as the vibrator levers are concerned, the strains at any one instant imposed 65 upon the heel pin by one half of the vibrator levers tending to move the heel pin to the right will be counter-balanced by the opposite strains exerted by the other vibrator levers tending to move the heel pin to the left, and under these 70 conditions there will be little or no tendency for the heel pin to bend. Where the pattern calls for an uneven lifting of the warps, however, and a preponderance of the threads are in the top shed, for instance, the strains exerted on the heel pin 75 will be unbalanced and the latter will tend to re-

flect in the direction of the greatest force exerted on it. As a result all of the vibrator levers and vibrator gears will be moved to an improper position, being displaced horizontally from their correct position. Where the load is heavy this deflection is sufficient to interfere with the proper operation of the head especially at high speeds where the strains are imposed quickly and the deflections correspondingly large. The resultant shift of the vibrator levers with respect to 10 the pattern chain and also of the vibrator gears with respect to their driving cylinders contribute to unsatisfactory operation. Furthermore, such deflection is transmitted to certain of the jacks, particularly those near the center of the head and 15 the shed is not as well defined as it should be and proper flighting of the shuttle.

The matter thus far described is of common construction and of itself forms no part of my present invention, and the conditions discussed 20 in connection with an unbalanced load are those encountered in a Knowles head of the usual construction.

My present invention has for its principal object to provide means for stiffening the heel pin 25 so that it will not deflect objectionably even when the load of the warp threads is greatly out of balance. In carrying my invention into effect I provide a heel shell 50 formed of angle iron or steel and having top and side webs 51 and 52, 30 respectively. The side web may be held to the plates 21 and 22 by screws 53 and the top web may lie between the plates 21 and 22, if desired, although I do not wish to be limited to this particular construction of the ends of the angle iron 35 heel shell. The top web 51 is of substantial proportions and as shown in Fig. 2 performs the usual function of heel shells, that is, it prevents upward motion of the vibrator levers relatively to the heel pin.

In order to establish a connection between the heel pin and the shell I provide a block 60 having a hole 61 therein which fits snugly around the heel pin. This block may have a top surface 62 which lies under and if desired in contact with 45 the bottom surface of the top web 51, and also has a vertical outer surface 63 which lies in contact with the inner surface of the vertical web 52. A screw 64 passes through the web 52 and into the block to hold the latter tightly against 50 the shell. As seen particularly in Fig. 2 it will be understood that the angle iron heel shell, the block and the heel pin are held together in close relationship. The block is preferably located as near the center of the head with respect to the 55 side plates 21 and 22 as is convenient and any horizontal strains such as those already described which are imposed upon the heel pin will be transmitted to and resisted by the shell through 60 the block.

From the foregoing it will be seen that I have provided a very simple means for stiffening the heel pins of a Knowles head and have also provided an improved form of heel shell. The particular means for uniting the shell and pin, as set 65 forth herein, constitutes a block, but inasmuch as I believe I am the first to connect the shell and pin for the purposes specified, I do not wish to be limited necessarily to a block.

As shown in Fig. 5, the end screws 53 pass 70 through vertical slots 70 in web 52 and screw 64 likewise passes through slot 71 in the web. The vibrators have top bosses 72 which lie close to the web 51, as shown in the Unwin patent mentioned. When the pattern mechanism lifts a vibrator 75

lever the latter pushes upwardly on the top web and the latter becomes the fixed part around which act the forces exerted on the lever.

Having thus described my invention it will be seen that changes and modifications may be made therein by those skilled in the art without departing from the spirit and scope of the invention and I do not wish to be limited to the details herein disclosed, but what I claim is:

- 10 1. In a head motion for looms, a vibrator lever, a loom part to be moved operatively connected to the lever and tending to move said lever horizontally, a heel pin to support the vibrator lever, a heel shell extending along the pin, and a connection between the shell and pin effective to cause the shell to reinforce the pin and assist cause the latter to resist horizontal motion of the vibrator lever.
- 20 2. In a head motion for looms, a vibrator lever, a loom part to be moved operatively connected to the lever and tending to move said lever horizontally, a heel pin to support the vibrator lever, a heel shell extending along the pin, and a block fitted around the pin and held to the shell to

cause the latter to resist horizontal motion of the vibrator lever.

3. In a head motion for looms, a vibrator lever, a loom part to be moved operatively connected to the lever and tending to move said lever horizontally, a heel pin to support the vibrator lever, a heel shell of angle section having a horizontal web, and a block held to the shell and having the heel pin passing therethrough, said block causing the shell to reinforce the pin against horizontal deflection. 5

4. In a head motion for looms, a vibrator lever, a fixed frame in which the lever is mounted, a vibrator gear rotatably mounted on the lever, a loom part operatively connected to the gear, a 15 heel pin fixed in the frame and on which one end of the lever is supported for pivotal motion, a bearing boss on the lever, a heel shell lying over the boss to limit upward motion of the lever, and a bolt and slot connection between the heel shell 20 and frame by which the shell is capable of assuming a plurality of positions at different distances from the heel pin to compensate for wear of the boss.

WILLIAM M. WATTIE. 25
